CLAIM

The ornamental design for a bag, as shown and described.

DESCRIPTION

FIG. 1 is a top, front, right perspective view of a bag showing our new design with a flap in a first position; FIG. 2 is front view thereof; FIG. 3 is a rear view thereof; FIG. 4 is a right side view thereof; FIG. 5 is a left side view thereof; FIG. 6 is a top view thereof; FIG. 7 is a bottom view thereof; FIG. 8 is a top, front, right perspective view of a collar showing our new design with the flap in a second position; FIG. 9 is front view thereof; FIG. 10 is a rear view thereof; FIG. 11 is a right side view thereof; FIG. 12 is a left side view thereof; FIG. 13 is a top view thereof; and, FIG. 14 is a bottom view thereof.

The uneven-length broken lines immediately adjacent to the shaded areas in FIGS. 1-14 define the bounds of the claimed design and form no part thereof. The uneven-length broken lines depicting the remainder of the bag in FIGS. 1-14 show features that form no part of the claimed design. The even-length broken lines in the drawings represent stitching and form no part of the claimed design.
